JOHAN KONKUS, OF FORDS, NEW JERSEY.

PERMUTATION DOUBLE LOCK.

Application filed October 13, 1927. Serial No. 225,885.

This invention relates to a permutation lock and its chief object is to provide an article of this character in which a combined door knob and key element may be used to throw its bolts and may be set with their component parts in such specific relation that the said bolts cannot be moved into their open positions unless the said parts are placed in the aforesaid specific relation.

Further objects are the provision of means for the re-arrangement of certain elements of the said knob and certain members within the lock casing, to form different coincident relations, or combinations by which the lock may be opened.

These and other objects and features of the invention will be fully described in the following specification and illustrated in the accompanying drawings, in which:

Fig. 1 shows a vertical cross section of the lock on the line 1—1 of Fig. 3.

Fig. 2 shows a front view of the knob illustrating the combination dials.

Fig. 3 shows the interior of the lock casing on the line 3—3 of Fig. 1; the back plate being removed.

Referring now to Fig. 1 of the drawings; the lock casing 10 is shown secured to the door 11 by means of the screws 12 and 13, other similar screws being placed at the corners of the casing. The casing elements comprise the front plate 14, side walls 15 and 16 and back plate 17. The back plate overlaps the casing and may be removed for access to the interior of the lock. The sleeve 18 passes through the woodwork of the door as shown. An escutcheon plate 19 is mounted concentric to the sleeve.

A key element 21 is provided with a square shoulder 22 to which is firmly affixed the dial ring B; the tubular shank 24 of the key element passes through the sleeve 18 and has, near to its extremity the bit 25, which bit is thin and flat as seen in Fig. 3; its inner portion is cut away as shown at 26 and from its base portion so as to have a horizontal portion 25; the extension 27 of the shank passes outward through the casing. Over this extension the cap 28 is secured by the screw 29. A groove 30 extends around the shank 24 and a longitudinal groove 31 opens into it as shown.

The central shaft 35 has affixed to its forward end the dial plate C. This shaft passes through the tubular shank 24 and has its rear end 36 reduced in diameter and pro-

truding within the cap 28. It is secured by the pin 37; at that portion of the shaft which rests within the open part 26 of the bit 25 it is provided with a series of teeth 38, the purpose of which will be described later.

The knob has a dial face A, and has its base portion rotatably mounted on the shank 24, its back rim 43 is perforated at intervals as seen at 44, 45 etc., and a pin 46 is mounted in one of the said perforations. This pin is secured by the ring 47 which may be removed for the purpose of changing its location. As may be seen, it engages the groove 31 and when the knob is pushed back, is adapted to pass around the groove 30 freely.

The dials A, B and C are each graduated as seen at 48, 49 etc. in Fig. 2, and each has a series of numerals as seen at 60, 61 etc.

Referring now more particularly to Fig. 3, the bolts 50 and 51 are placed flat within the casing and are guided at the top and the bottom thereof by the lugs 52, 53, 54 etc. They are maintained in their longitudinal relation by the connector 55 which engages the lower bolt as seen at 56. At the forward and rear extremities the bolts are of a thickness equal to the interior depth of the lock casing, but in the central portions between the dotted lines 57 and 58; and 59 and 60, they are cut away to give clearance for the interior mechanism. The bolt 50 has a slot 62 which engages the bit 25 and a slot 63 which is adapted to receive the stop latch 64, and the bolt 51 has a slot 65 which is adapted to receive the stop latch 66. These stop latches are provided with end springs 67 and 68 and are under pressure of the springs 69 and 70. The cross bar 73 has a center ring 74 which is notched to fit over the teeth 38 of the central shaft. A ratchet spring 75 is secured to the boss 76 and serves to hold the said central shaft in the desired position by engaging the teeth 38, but permits of its rotation when required.

In the illustrations the lock is shown with the bolts thrown out, but not locked. The release of the latches 64 and 66 by turning the dial C will accomplish this by the said latches engaging the adjacent slots in the said bolts. This done, and the dials spun into random relation with each other, and the knob 42 pushed back so that the pin is in the rotation groove; the lock cannot be opened except by a proper setting of the dials and rotation of the knob as will now be described.

Assuming the combination to be 3—6—2 reading inward from the A dial; in its locked position, the bit 25 will be vertical and its dial ring B will, as in the illustration, have the 6 at the top. The knob will still be pushed back as it was left after locking. The knob is now rotated until its dial numeral 3 on the face is in line with the 6 on the B dial, it may then be drawn forward 10 as the pin 46 will now coincide with the longitudinal groove, and it is now in position to rotate the shank 24 as soon as the latches 64 and 66 are thrown out of the bolt slots. This is done by rotating the dial C 15 to the right until it stops against the horizontal portion 25' of the bit, it is then turned to the left until its dial numeral 2 is in line with the 3 and 6 already set; in this position, which is as shown in Fig. 3, 20 the latches will be free from the slots and the bolts may be thrown open by rotating the knob.

While I have shown and described the preferred embodiment of the invention in 25 the accompanying drawings and specification, I do not wish to be held rigidly to the exact details of this construction, but claim the right to such minor modifications as may come within the spirit and scope of the appended claims.

Having thus described my invention, what I claim as new and desire to secure by Letters Patent, is as follows:

1. In a lock of the class described, a casing, slideable bolts within the said casing, latch members engageable with the bolts a tubular shank passing within the said casing and means thereon to actuate the said bolts, a dial element on the outer extremity 35 of the said tubular shank, a knob rotatably mounted about the said dial element, a central shaft passing through the said tubular shank, a dial element on the said shaft, means on the said central shaft to actuate the 40 said latches within the said casing, and suit-

able characters on the face of the said dial elements.

2. In a lock of the character described, the combination with a lock casing having therein slideable bolts, and latch members 50 engaging the same, of a tubular shank having a key bit thereon, a knob consisting of concentric rotatable elements, and a central shaft passing through the said shank and having thereon a dial element adapted to 55 coact with the said rotatable elements and having mounted thereon, at a point within the said lock casing, a transverse element which is adapted to engage the aforesaid latch members when all of the rotatable elements are in a certain specific relation to each other and to move the said latch members into inoperative positions.

3. In a lock of the character described, the combination with a lock casing having 60 therein slideable bolts and latch members engageable therewith, of a tubular shank entering the said casing and provided with a key bit on that portion within the said casing and with a knob at its extremity, which 65 knob comprises a plurality of dial elements having thereon suitable markings, the outer dial element extending back over and bearing upon the said shank and having a pin member in engagement with a groove in the 70 said shank, which groove extends longitudinally thereto and communicates with a second groove running around the circumference of the said shank, and a central shaft 75 having a dial element concentric to those first described and the said shaft passing through the said tubular shank and having at a point adjacent to the key bit, a transverse member, which member, upon rotation is adapted to engage the latch members which 80 act upon the said slideable bolts.

In testimony whereof I have affixed my signature.

JOHAN KONKUS.
